UNITED STATES PATENT OFFICE.

CHARLES C. BALDWIN, OF MOMENCE, ILLINOIS, ASSIGNOR OF ONE-FOURTH
TO LEON J. TIFFANY, OF MOMENCE, ILLINOIS.

LUBRICANT-ATOMIZER.

SPECIFICATION forming part of Letters Patent No. 715,940, dated December 16, 1902.

Application filed June 5, 1902. Serial No. 110,300. (No model.)

To all whom it may concern:

Be it known that I, CHARLES C. BALDWIN, a citizen of the United States, and a resident of Momence, in the county of Kankakee and State of Illinois, have invented a new and Improved Lubricant-Atomizer, of which the following is a full, clear, and exact description.

This invention relates to means for lubricating the valves and interiors of steam-engine cylinders, pump-cylinders, or like portions of other motors using live steam or any other source of power—such as compressed air, gas, &c.—as a motive agent, and has for its object to provide a novel simple device of the character indicated which is adapted to reliably distribute oil or other lubricant in an atomized condition to the interior parts of a steam-motor requiring periodic or continuous lubrication.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a sectional side view of the improvement applied within a steam-pipe. Fig. 2 is a sectional plan view substantially on the line 2 2 in Fig. 1, and Fig. 3 is a reversed plan view of the atomizer.

The atomizer comprises a tubular body 5, having a lateral outlet 6, wherein screws one end of the oil-supply pipe 7. The upper end 5^a of the body 5 is preferably flared to adapt it to receive freely a volume of steam. The lower end of the body 5 is provided with a deflecting-flange 5^b, which extends a suitable distance outside of the bottom wall 5^c, that closes said lower end of the body, and affords an annular projection, that may be concaved on the upper side, as shown in Fig. 1, and also is annularly channelled on the lower side 45 near the edge of said bottom wall, as shown at 5^d in Fig. 3.

In the body 5 of the atomizer, adjacent to the dished upper surface of the deflecting-flange 5^b, a plurality of radial spaced perforations *a* are formed. 8 indicates a portion of a live-steam pipe extending in complete form

from a source of steam-supply to a steam-motor cylinder that is to be lubricated, the steam being inducted in the direction of the arrow *x* in Fig. 1. The oil-supply pipe 7 is inserted through a stuffing-box 9, provided to receive it, this stuffing-box, which is of ordinary construction, affording means for packing the joint formed between the apertured wall of the steam-pipe 8 and the oil-feeding pipe where the latter passes through the steam-pipe. The pipe 7, which is shown broken away, in practice is extended to a source of oil-supply, which may be a sight-feed lubricator of any approved construction.

The operation is as follows: Steam passing in the direction of the arrow *x* in the steam-pipe 8 meets a graduated amount of oil or other lubricant introduced into the bottom of the body 5 by the oil-feeding pipe 7. The pressure of the dry steam that occupies the atomizer-body 5 causes the steam and oil in commingled condition to pass out of the perforations *a*, and thereby vaporize the lubricant, which mixes with the steam and in finely-divided condition coats the valves, the piston, the surface of the cylinder, and the piston-rod of the steam-actuated motor, thereby effectively lubricating these parts. The concavity on the upper side of the annular flange 5^b serves to retain a small amount of lubricant when the operation of the lubricator device is started, which modicum of oil receives the impact of downflowing steam in the tubular body 5, which spreads it outwardly and upwardly, so that it is brought into intimate contact with the steam that pervades the bore of the steam-pipe 8. By the provision of a suitable oil-feeding device the influx of lubricating liquid may be graduated and controlled, so that the supply to the interior of the motor may be continuous while the same is in operation or be periodic, as best suits the requirement of the motor with which the improved oil-atomizing device is connected.

Having described my invention, I claim as new and desire to secure by Letters Patent—

1. A lubricant-atomizer, comprising a tubular body closed at the lower end, and flared at the upper end, said body having radial per-

forations in its side wall near the closed lower end thereof, a radial flange below and near the radial perforations, and a lubricant-supply pipe communicating with the side wall of the lubricant-atomizer body between its ends.

2. A lubricant-atomizer held centrally and vertically in a live-steam pipe for impregnating live steam passing down in the pipe with atomized lubricant, said atomizer comprising a tubular body open at the upper end, closed at the lower end, and having a row of spaced perforations in the tubular wall adjacent to the closed bottom and leading radially to the exterior, a radial flange formed on the tubu-

lar body immediately below the spaced radial 15 perforations in said body, and a lubricant-supply pipe extended laterally through the live-steam pipe and communicating with the side of the tubular body between its upper and lower ends.

In testimony whereof I have signed my name to this specification in the presence of two subscribing witnesses.

CHARLES C. BALDWIN.

Witnesses:

VICTOR T. BRASSARD,
GEORGE HOPPER.

Corrections in Letters Patent No. 715,940.

It is hereby certified that in Letters Patent No. 715,940, granted December 16, 1902, upon the application of Charles C. Baldwin, of Momence, Illinois, for an improvement in "Lubricant-Atomizers," errors appear requiring the following corrections, viz: In line 7, of the grant and in the printed head of the specification, it is stated that said Baldwin assigned "one-fourth" to Leon J. Tiffany, whereas it should have been stated that he assigned *three-fourths*; and that the said Letters Patent should be read with these corrections therein that the same may conform to the record of the case in the Patent Office.

Signed and sealed this 13th day of January, A. D., 1903.

[SEAL.]

F. I. ALLEN,
Commissioner of Patents.
